United States Patent Office

Des. 187,888
Patented May 10, 1960

187,888

JAR

Alfred A. Anthony, New York, N.Y., assignor to Revlon,
Inc., New York, N.Y., a corporation of Delaware

Application November 6, 1959, Serial No. 58,227

Term of patent 14 years

(Cl. D58—25)

FIG. 1

FIG. 2

FIG. 3

Fig. 1 is a top plan view of a jar, showing my new design;

Fig. 2 is a side elevational view thereof;

Fig. 3 is a bottom plan view thereof.

The top and bottom bands of the surface ornamentation include three repeats of the pattern as viewed in Fig. 2 and completely encircle the jar.

I claim:

The ornamental design for a jar, as shown and described.
